(57) **CLAIM**

The ornamental design for a glider frame, as shown and described.

DESCRIPTION

FIG. 1 is a perspective view of a glider frame according to the present invention;

FIG. 2 is a front view thereof;

FIG. 3 is a right side view thereof, a left side view being a mirror image thereof;

FIG. 4 is a top view thereof;

FIG. 5 is a rear view thereof; and,

FIG. 6 is a bottom view thereof.

The glider seat shown in broken lines is merely an example and forms no part of the claimed design.
